UNITED STATES PATENT OFFICE.

RUSSELL HUFF, OF DETROIT, MICHIGAN, ASSIGNOR TO PACKARD MOTOR CAR COMPANY, OF DETROIT, MICHIGAN, A CORPORATION OF WEST VIRGINIA.

STARTING DEVICE FOR HYDROCARBON-ENGINES.

No. 896,112.

Specification of Letters Patent. Patented Aug. 18, 1908.

Application filed November 30, 1907. Serial No. 404,522.

To all whom it may concern:

Be it known that I, RUSSELL HUFF, a citizen of the United States, and resident of Detroit, Wayne county, State of Michigan, have 5 invented certain new and useful Improvements in Starting Devices for Hydrocarbon-Engines, of which the following is a specification.

This invention relates to improvements in 10 motor vehicles and more particularly to means for opening the throttle and retarding the spark while starting the motor, whereby the possibility of "back kicking" of the starting crank is precluded.

15 The invention will be described in connection with the accompanying drawing, in which,

Figure 1 is a side elevation of so much of the motor mechanism of the vehicle as is necessary to illustrate the invention, the parts being shown in the position which they assume when the vehicle is not running or running slowly; Fig. 2 is a similar view showing the parts in the position assumed when the 25 engine is being cranked; Fig. 3 is a diagram of the commutator; Fig. 4 is a section through the mixture inlet pipe showing the valves therein.

Referring to the drawing, 1 indicates the 30 body of a motor vehicle, 2 the dash-board, 3 the radiator, 4 the cylinder casings of the engine, and 5 the inlet pipe which is provided with branches 6 leading to the cylinders within the casings 4. Within the mixture 35 pipe 5 is a valve 7 which is connected through arm 8, link 9 and lever 10 with a governor G. The valve 7, which is of any suitable structure, stands normally open. When, however, the motor starts the governor shifts the 40 lever 10 closing this valve more or less, depending upon the speed of the engine. As shown the valve 7 is beyond the control of the driver of the vehicle and in some classes of vehicles this is a desirable feature as the 45 governor can be so adjusted as to close the valve when the motor reaches a prescribed limit, thus preventing the driver from exceeding the speed limit at which the governor is set. In the inlet pipe is also arranged a 50 valve 11 which is operated by an arm 12. The arm 12 is connected with the usual accelerator pedal 13 by means of a link 14 and a spring 15 holds the pedal in its elevated position and the valve 11 normally closed. A

by-pass 16 is provided whereby sufficient 55 mixture is permitted to enter the motor to operate it at ordinary speeds while the valve 11 is closed.

A link 17 is connected at one end with the arm 12 by a pin-and-slot connection and at 60 the other end it is pivotally connected with one arm of a rocking lever 18, the other arm of said lever being engaged with an annular groove 19 on the clutch member 20 of the starting crank 21 by means of which the engine is cranked. In starting the motor it is desirable to have the valves in the mixture inlet pipe wide open so that an ample supply 65 of mixture can pass to the motor. By the arrangement above described the valve 11 is 70 moved from its closed position, as shown in Figs. 1 and 4, to its open position, as shown in Fig. 2, when the crank is moved inward to its operative position, shown in Fig. 2. As the valve 7 stands normally wide open when 75 the motor is stopped, it will be seen that both valves are open during the cranking operation. When through cranking, the clutch member 20 is automatically withdrawn from its complementary clutch member 22 by the 80 spring 23 and the valve 11 is closed by the spring 15. The pin-and-slot connection between the arm 12 and the link 17 permits the accelerator pedal 13 to be operated at any time without disturbing the cranking clutch 85 20. It is also desirable to retard the spark while cranking to prevent premature explosion and for this reason I connect the rocking post 24 which carries the commutator 25 with the starting crank 21. As shown, this 90 connection is accomplished by means of an arm 26 on the post, link 27 and arm 28 on the rock shaft 29 which carries the lever 18. A spring 30 holds the commutator in its normal position and a pin-and-slot connection between the link 27 and the arm 28 permits of 95 the usual adjustment of the commutator without disturbing the crank shaft.

It will be seen that before the crank can be 100 operated to turn the engine the throttle valve 11 must be opened and the commutator arranged to retard the spark, under which conditions a premature explosion resulting in a back kick is practically impossible and it will also be evident that I accomplish these 105 results without in any way interfering with the normal operation of the engine and its usual controlling means.

Having described my invention what I claim and desire to secure by Letters-Patent, is,

1. In controlling means for motor vehicles, the combination with the mixture inlet pipe and a throttle valve therein, of a starting crank for the engine and connections between the starting crank, and the throttle valve whereby the latter is opened when the crank is moved to operative relation with the engine.
2. In controlling means for motor vehicles, the combination with the mixture inlet pipe and the throttle valve thereof, of a starting crank, a clutch for connecting the starting crank with the engine, means for normally holding the clutch open, means for normally holding the said throttle valve closed, and a connection between the throttle valve and the starting crank, whereby the former is opened when the latter is moved to operative position.
3. In controlling means for motor vehicles, the combination with the mixture inlet pipe and the throttle valve thereof, of a starting crank, a clutch for connecting the starting crank with the engine, means for normally holding the clutch open, means for normally holding the said throttle valve closed, a connection between the throttle valve and the starting crank, whereby the former is opened when the latter is moved to operative position, said connection comprising a lever engaging the shaft of the starting crank, an arm on the valve, and a link connecting said lever and said arm.
4. In controlling means for motor vehicles, the combination with the mixture inlet pipe and the throttle valve thereof, of a starting crank, a clutch for connecting the starting crank with the engine, means for normally

holding the clutch open, means for normally holding the said throttle valve closed, a connection between the throttle valve and the starting crank, whereby the former is opened when the latter is moved to operative position, said connection comprising a lever engaging the shaft of the starting crank, an arm on the valve, and a link connecting said lever and said arm, the said link having a pin-and-slot connection with one of said parts.

5. In controlling means for motor vehicles, the combination with the mixture inlet pipe, of a throttle valve in said pipe, an accelerator pedal connected to said valve, and a starting crank also connected to said valve, the said valve being adapted to be opened either by the accelerator pedal or the starting crank.

6. In controlling means for motor vehicles, the combination with the mixture inlet pipe, the throttle valve therein, and the commutator, of a starting crank, and connections between said starting crank and said throttle valve and commutator respectively, whereby the throttle valve is opened and the spark retarded during the cranking of the engine.

7. In controlling means for motor vehicles, the combination with the mixture inlet pipe, the throttle valve therein and the commutator, of a starting crank, and pin-and-slot connections between said starting crank and said throttle valve and commutator respectively, whereby the throttle valve is opened and the spark retarded during the cranking of the engine.

In testimony whereof I affix my signature in presence of two witnesses.

RUSSELL HUFF.
